UNITED STATES PATENT OFFICE.

SARAH A. M. BAYER, OF NEW YORK, N. Y.

NON-REFILLABLE BOTTLE.

1,175,502.

Specification of Letters Patent.

Patented Mar. 14, 1916.

Application filed June 22, 1915. Serial No. 35,663.

To all whom it may concern:

Be it known that I, SARAH A. M. BAYER, a citizen of the United States, residing at New York, in the county of New York and State of New York, have invented certain new and useful Improvements in Non-Refillable Bottles, of which the following is a specification.

This invention relates to attachments to bottles to prevent surreptitious refilling of the bottle, and has for one of its objects to improve the construction and increase the efficiency and utility of devices of this character.

Another object of the invention is to provide a device of this character adapted to be applied to the bottle without materially increasing the expense of the construction of the bottle, or rendering it necessary to fracture the bottle in order to remove the contents.

With these and other objects in view, the invention consists in certain novel features of construction as hereinafter shown and described and then specifically pointed out in the claims; and in the drawings illustrative of the preferred embodiment of the invention Figure 1 is a vertical sectional elevation of the improved device applied. Fig. 2 is a side elevation of the improved device located in the neck of a bottle, the neck and a portion of the body of the bottle being in section. Fig. 3 is a transverse section on the line 3—3 of Fig. 1. Fig. 4 is a detached perspective view of the plug portion of the improved device. Fig. 5 is a side view of a modified form of the outer shell member. Fig. 6 is a side view of a modified form of the valve.

Corresponding and like parts are referred to in the following description and indicated in all the views of the accompanying drawings by the same reference characters.

A portion of the body of the bottle is represented at 10 and the neck portion at 11, the latter being slightly tapered from end to end with the smaller diameter next to the body of the bottle.

The improved device is located within the neck of the bottle and comprises four parts, an outer shell-shaped member 12 closed at the outer end and open at the inner end, a plug member, indicated as a whole at 13, and bearing against the lower open face of the shell, an annular member, represented as a whole at 14, and secured within the neck

11 of the bottle at its juncture with the body 10 and having a seat 15 to receive a valve 16, the latter being preferably tapered, and with a depending guide stem 17. Suspended from the stem 17 by a flexible cord or like member 18 is a bar or stop 19 enlarged at the ends, as shown at 20. Depending from the lower face of the plug 13 is a stop 21 to limit the upward movement of the valve, as illustrated in Fig. 1.

The outer closed end 22 of the shell 12 is smaller in diameter than the diameter of the bottle neck, and between the outer end 22 and the body of the shell 12 an annular channel 23 is formed, and leading inwardly through the bottom of the channel are a plurality of orifices 24 through which the liquid flows, as hereinafter explained.

Formed in the plug 13 at one side is a relatively large cavity 25 opening at its outer end into the interior of the shell 12 and with its inner end closed. Formed in the plug 13 at the opposite side is a cavity 26 opening downwardly into the space between the valve seat 14 and the plug. Formed through the plug 13 is a transverse passage 27 communicating at its inner end with the cavity 25 and likewise communicating with the cavity 26. The passage 27 is located above the lower line of the cavity 25, as illustrated in Fig. 1, to baffle attempts to introduce a wire or other implement to displace the valve 16.

A relatively small vent orifice 28 is formed through the body of the plug 13 and provides communication between the interior of the shell 12 and the passage 27, and preventing the formation of air pockets in the passages or cavities. By this simple arrangement, it will be obvious that, when the bottle is standing erect, the valve 16 will remain closed by gravity and effectually prevent the introduction of any liquids into the body of the bottle, but if the bottle be turned upon its side or inverted, the valve 16 will open by gravity and allow the liquid to flow through the cavities 25—26 and the passage 27 into the shell 12 and thence out through the orifices 24, and then, when the bottle is restored to its vertical position, the valve 16 will be automatically closed by the action of the member 19—20 and prevent the introduction of any liquid into the bottle.

It will be noted that the shell 12 is located some distance below the outer or lip

portion of the neck 11 of the bottle so that an ordinary cork can be inserted in the neck externally of the shell and the other attachments, but the cork is not shown as it forms no part of the present invention. The shell 12, plug 13, and annular seat 14 will preferably be secured in position by cementing or by other suitable means and are not detachable after once being inserted.

- 10 In Fig. 5 a slight modification is shown in the construction of the shell 12, consisting in forming the outer portion 22 equal in diameter to the inner walls of the neck 11 and forming a plurality of notches 29 in the edge of the portion 12 and likewise forming a portion of the vents 24 through the closed outer end 22 of the shell.

In Fig. 6 a slightly modified form of the valve is shown.

- 20 Having thus described the invention, what is claimed as new is:

1. In a device of the class described, a shell closed at the outer end and adapted to be secured in the neck of a bottle and having an annular depression near the outer end with the portion of the shell externally of the depression of less diameter than the body of the shell and with a plurality of orifices in the depression providing communication with the interior of the shell, a plug adapted to be disposed in the neck of said bottle and closing the inner end of the shell, said plug having passages at opposite sides communicating respectively with the interior of the shell and with the neck of the bottle and connected by a transverse passage, and an outwardly opening valve adapted to be supported in the neck of said bottle between the plug and the body of the same.

Copies of this patent may be obtained for five cents each, by addressing the "Commissioner of Patents, Washington, D. C."

2. In a device of the class described, a shell closed at the outer end and adapted to be secured in the neck of a bottle and having transverse orifices, a plug adapted to be disposed in the neck of said bottle and closing the inner end of the shell, said plug having an outwardly opening cavity communicating with the interior of the shell, an inwardly opening cavity communicating with the interior of the neck of the bottle and a passage connecting the cavities, said passage being located above the bottom of the outwardly opening cavity to prevent the introduction of a valve manipulating implement, and an outwardly opening valve adapted to be supported in the neck of said bottle between the plug and the body of the same.

3. In a device of the class described, a shell closed at the outer end and adapted to be secured in the neck of a bottle and having transverse orifices, a plug adapted to be disposed in the neck of said bottle and closing the inner end of the shell, said plug having an outwardly opening cavity communicating with the interior of the shell, an inwardly opening cavity communicating with the interior of the neck of the bottle and a transverse cavity opening through the sides of the plug and communicating at one portion thereof with the outwardly opening cavity and communicating at another portion with the inwardly opening cavity, and an outwardly opening valve adapted to be supported in the neck of said bottle between the plug and the body of the same.

In testimony whereof I affix my signature.

SARAH A. M. BAYER. [L.S.]
